UNITED STATES PATENT OFFICE

ARBA G. WILLIAMSON, OF CARNEGIE, PENNSYLVANIA, ASSIGNOR, BY MESNE ASSIGNMENTS, TO THE UNION SWITCH & SIGNAL COMPANY, OF SWISSVALE, PENNSYLVANIA, A CORPORATION OF PENNSYLVANIA

TRACK-CIRCUIT SYSTEM

Original application filed April 5, 1922, Serial No. 549,662, Patent No. 1,683,222, dated September 4, 1928.
Divided and this application filed August 16, 1928, Serial No. 299,885.

This invention relates to track circuit systems particularly for use in connection with train control systems of the type disclosed in applications Serial No. 555,304, filed April 18, 1922 and is a division of application Serial No. 549,662, filed April 5, 1922, which has matured into Patent No. 1,683,222, dated September 4, 1928.

The main object and feature of the invention is to provide a simple form of track circuit means whereby an interrelated control between a plurality of track circuits may be effected.

More particularly this invention relates to a track circuit system for use with train control systems of the type comprising train carried means controlled by energy received from circuits including the traffic track.

In the accompanying drawing a preferred form of the invention is disclosed, the drawing showing a diagrammatic view of the track circuit system.

Referring to the drawing, 1 and 2 represent the rails of a traffic track divided into blocks W, X, Y and Z in a manner well understood by means of insulation 3. 4 and 5 indicate line wires fed by a single frequency generator G. Associated with each block is a main transformer indicated by Tw, Tx and Ty. The secondary 6 of each of these transformers is connected by means of conductors 7 and 9 with a primary 8 of a track transformer associated with each block and indicated variously as Nw, Nx and Ny. The secondary 13 of each of the respective track transformers is connected by suitable leads with rails 1 and 2 thereby supplying current to both of said rails of a given block. Interposed between secondary 6 of the main transformer and primary 8 of the track transformer is a circuit breaker in the form of a pole changer designated as Pw, Px and Py for the respective blocks W, X and Y.

Each block is also provided with a track relay designated as Lx, Ly and Lz. These track relays are of the two element polarized type that is well known in the art. One element is connected by suitable leads to the traffic rails of a block. The second element Q of each relay is connected to the wires 7 and

9 and therefore fed by the secondary 6 of the main transformer T.

Thus these polarized track relays are influenced both by the track circuit current and by current from transformer T.

It is well known that where the instantaneous polarity of both elements is such that the currents in both elements are in phase that the armature 100 will swing to one position, let us say, to right hand position. If the connection of one element should be reversed so that the instantaneous polarity of the currents in the two elements are out of phase then armature 100 will swing to the left hand position. If current is absent in the track element then armature 100 will hang in a center position. Reversal of the instantaneous polarity of the current in the track rails is accomplished by the pole changer reversing the connections to the primary of the track transformer.

The pole changer is actuated by a repeater relay 150, which is connected by wire 151 to the wire 9, and to the wire 7 through either the left hand contact 152 or right hand contact 153 and the armature 100 of the track relay with which it is associated. Thus the repeater relay 150 for a block is energized when the track relay is energized with either normal or reverse polarity of current and is deenergized when the track relay is deenergized.

In addition to the above described track circuit which includes the traffic track, each block is provided with a second track circuit which also includes the traffic track.

Connected to one side of the secondary 6 leads conductor 101, impedance 102, wire 103 and to ground. Again from the primary 8 of the track transformer N leads the shunt connection 105 to the wire 14 leading to the rail 1 of the traffic track.

Inasmuch as the rails of the traffic track are to a certain extent insulated from ground, the circuit just traced will establish a potential on the traffic track that is above ground potential. That is to say the insulation is of course not perfect and while there exists a leakage of current it is not excessive so that

voltage above ground potential is maintained on the traffic track of the block.

While the current flowing in the first described track circuit is preferably used to influence a coordinating train carried circuit as well as to control wayside circuits, the second described track circuit is to be used to influence a coordinating train carried circuit.

When a train K occupies the block Z as shown in the drawing, the track relay L_z is deenergized and its armature 100 drops to the center position thereby rupturing the circuit through the repeater relay $150z$. Relay $150z$ dropping the pole changer P_y causes current of one polarity to be supplied to the track transformer N_y . Also dropping of P_y cuts out the energizing of the second track circuit for the block Y, inasmuch as the lead to the ground and the shunt lead around the track transformer N_z are both connected to the same terminal of the secondary of the main transformer T_y . Thus the traffic track of block Y to the rear of the occupied block Z is supplied with but one current.

The reverse current flowing in the block Y energizes the track relay L_y so that its armature 100 swings to the left hand position to close the circuit to the repeater relay $150y$. Relay $150y$ being now energized lifts the pole changer P_x whereby the first track circuit of the block X is supplied with current of normal polarity. Furthermore, the lifting of pole changer P_x causes the second track circuit for the block X to be energized by the following circuit: secondary 6 of T_x , wire 9, lower arm of pole changer P_x , wire 7, wire 105, wire 14, impedance and to rail 1, and the opposite terminal of secondary 6, wire 7, wire 101, impedance 102, wire 103 and ground.

Thus the traffic track of the block X, the second block to the rear of the occupied block Z, is supplied with two currents.

I claim:

1. A track circuit system including: a traffic track divided into blocks, two normally closed track circuits for each block, each of which circuits includes the traffic track, a polarized relay for each block energized by one of said track circuits, a repeater relay for each block energized when the said polarized relay of the same block is energized with either normal or reverse polarity of current, and deenergized when said polarized relay is deenergized, and a circuit breaker controlled by said repeater relay to reverse the polarity of the current supplied to the track circuit that energizes the polarized relay of another block and to permit and prevent the energization of the second track circuit of said other block.

2. A track circuit system including a traffic track arranged in blocks, two normally closed track circuits for each block, each of which circuits includes the traffic track, a polarized relay for each block energized by

one of said track circuits, and a second relay for each block controlled by the polarized relay of that block, said second relay arranged, when the polarized relay by which it is controlled is energized by either normal or reverse polarity of current, to permit current of normal polarity to be supplied to the track circuit that energizes the polarized relay for the block in the rear, and also to permit the energization of the second track circuit for the said block in the rear, and said second relay arranged to permit current of reverse polarity to be supplied to the track circuit that energizes the polarized relay for the block in the rear and to prevent energization of said second track circuit for the block in the rear when the polarized relay by which said second relay is controlled is deenergized.

3. A track circuit system including a traffic track arranged in blocks, two normally closed track circuits for each block, each of which circuits includes the traffic track, a polarized relay for each block controlled by one of said track circuits, a repeater relay associated with each polarized relay and controlled thereby, and armatures actuated by said repeater relay arranged to control the polarity of the current being supplied to the track circuit that controls the polarized relay of another block and to permit and prevent the supplying of current to the other track circuit of said other block.

4. A track circuit system including: traffic track arranged in blocks, two normally closed circuit means for supplying current to the traffic track of each block, a polarized relay for each block energized by current supplied to the traffic track by one of said circuit means, and a second relay for each block controlled by the polarized relay of that block, said second relay arranged, when the polarized relay that controls said second relay is energized by either normal or reverse polarity of current, to permit current of normal polarity to be supplied to the traffic track for the block in the rear by the circuit means that energizes the polarized relay of said block in the rear, and also to permit current to be supplied to the traffic track for said block in the rear by the second circuit means of said block in the rear, and said second relay arranged, when the polarized relay by which said second relay is controlled is deenergized, to permit current of reverse polarity to be supplied to the traffic track for the block in the rear by the circuit means that energizes the polarized relay, and to prevent current to be supplied to the traffic track for the block in the rear by the second circuit means.

Signed at Washington, in the District of Columbia, this 16th day of August, 1928.

ARBA G. WILLIAMSON.
